UNITED STATES PATENT OFFICE

2,541,467

RESTAURANT COUNTER RACK

Philip J. Duginski, Pittsfield, Mass.

Application February 18, 1949, Serial No. 77,209

2 Claims. (Cl. 312—140.4)

1

This invention relates to a novel rack for use on restaurant or lunch counters where customers are served to provide a rack or holder for a napkin dispenser, menu, sugar dispenser, salt shaker and pepper shaker and by means of which said elements may be held conveniently assembled for use by a patron.

A primary object of the present invention is to provide a counter rack or holder which is fastened to the counter and which is capable of readily being swung out of engagement with the upper surface thereof to enable the counter to be cleaned and maintained in a sanitary condition and to facilitate cleaning of the rack or holder.

Various other objects and advantages of the invention will hereinafter become more fully apparent from the following description of the drawings, illustrating a presently preferred embodiment thereof, and wherein:

Figure 1 is a top plan view showing the rack or holder in an applied position;

Figure 2 is a front elevational view thereof;

Figure 3 is a rear elevational view of the same;

Figure 4 is a sectional view, partly in elevation taken substantially along a plane as indicated by the line 4—4 of Figure 1;

Figure 5 is a side elevational view, partly in section, showing the holder moved to a position to facilitate cleaning of the counter or surface on which it is normally disposed, and

Figure 6 is an enlarged cross sectional view taken substantially along a plane as indicated by the line 6—6 of Figure 1.

Referring more specifically to the drawings, the novel counter rack or holder in its entirety is designated generally 7 and includes a substantially straight intermediate portion 8 having corresponding integral leg portions 9 which project at obtuse angles from the ends of said intermediate portion and in outwardly diverging relationship to one another. The portions 8 and 9 are of hollow or tubular construction and of rectangular cross section, as best seen in Figures 4 and 6, except for the outer end portions of the legs 9 which are preferably beveled on their inner sides as seen at 10.

The intermediate portion 8 is provided at its bottom outer edge with a normally depending hinge leaf 11 which is hingedly connected to said portion 8 and which is provided with openings to receive screws or other driven fastenings 12 for attaching the hinge leaf 11 to the back edge of a counter or similar element 13 so that the rack portions 8 and 9 may rest substantially

2

flush on the upper surface of the counter or element 13, as seen in Figures 2, 3 and 4 or so that said rack portions 8 and 9 may be swung upwardly and backwardly on the hinge leaf 11 to expose the upper surface of the portion of the counter 13 on which said parts normally rest, as seen in Figure 5.

Each of the legs 9, nearer to but spaced from its free end is provided with a pin or post 14 having a lower end extending perpendicularly through said leg 9, as seen in Figure 6 and which is suitably anchored thereto and which post or pin 14 extends upwardly to a point substantially above the normal level of the upper surface of the legs 9. The posts or pins 14 are preferably provided with enlargements or knobs 15 at their upper ends.

The intermediate portion 8 is provided with a shield 16 which is preferably formed integral therewith or which may be suitably secured thereto and which extends upwardly from the inner side thereof and which preferably extends substantially the entire length of said inner side, between the inner ends of the legs 9. The shield 16 has an arcuate upper edge and ends extending from end-to-end thereof, as clearly illustrated in Figure 3.

The rack or holder 7 including the parts 8, 9, 11, 14, 15 and 16 is preferably formed of stainless steel or other durable material which may be readily maintained in a clean and sanitary condition.

The portions 8 and 9 of the rack 7 may be made in various sizes but are preferably of a size so that a conventional napkin dispenser 17 such as is used in restaurants and lunchrooms may be positioned against the inner surface of the portion 8 and shield 16 and between the legs 9 and so that the front thereof will be spaced inwardly from the pins or posts 14, as seen in Figure 1, to enable a menu 18 to be rested on the legs 9 and supported on one side by the napkin dispenser 17 and on the other side thereof by the knobs 15 of the post 14 or by a conventional shaker-type sugar dispenser 19 which is positioned between the legs 9 and on the opposite, outer side of the menu 18. There is also sufficient space between the sugar dispenser 19 and the outer portions of the legs 9 to accommodate a salt shaker 20 on one side of the dispenser 19 and a pepper shaker 21 on the opposite side thereof.

It will be readily obvious that the menu 18 can be readily removed from its position on the rack 7 thus exposing the two sides of the napkin dis-

dispenser 17 located adjacent the legs 9 so that a napkin can be extracted in a conventional manner from either of said sides and with the dispenser 17 being held against lateral displacement relatively to the rack 7 by the legs 9. Likewise, the sugar, salt or pepper shaker may be removed from its position of Figure 1 without affecting the support of the menu 18 which will still be supported on the rack 7 between the posts 14 and napkin dispenser 17.

For the purpose of cleaning the upper surface of the counter 13, the items 17, 18, 19, 20 and 21 may be removed from the rack 7 and placed to one side thereof on the counter 13 after which the rack portions 8 and 9 may be swung on the hinge leaf 11 in a clockwise direction from their positions of Figure 4 to or beyond their positions of Figure 5 so that the surface of the counter 13 on which the portions 8 and 9 normally rest may be readily cleaned. It will be readily apparent that the rack portions 8 and 9 may be swung clockwise from their positions of Figure 4 through an arc of substantially 180° and may be held in any one of their intermediate positions, as for example in the position of Figure 5, so that all parts of the rack may be readily cleaned.

The rack 7 may obviously be made in various sizes to accommodate napkins and dispensers of different sizes and could also be utilized for retaining other items such as cream dispensers and syrup dispensers in a desired position on a counter. It will likewise be readily apparent that the rack 7 could be mounted on other surfaces than a counter such as a table top.

Various other modifications and changes are contemplated and may obviously be restored to, without departing from the spirit or scope of the invention as hereinafter defined by the appended claims.

I claim as my invention:

1. A counter rack of the character described comprising an intermediate rack portion, leg portions projecting from the ends of said intermediate portion in diverging relationship to one another, said intermediate portion and leg portions being disposed in the same plane and being adapted to normally rest on the upper surface of a counter or the like and combining with the portion of the counter surface on which the rack rests to provide a three sided frame for said surface portion, a hinge leaf pivotally connected to the outer edge of said intermediate portion and adapted to be secured to a side edge of the counter for swingably connecting the intermediate portion and legs of the rack to said edge of the counter for swinging movement in a direction upwardly and away from the upper surface thereof, and means rising from said intermediate portion and leg portions and combining therewith for retaining a plurality of articles in a predetermined position relatively to the portion of the upper surface of the counter partially framed by the rack.

2. A rack as in claim 1, said means including pins extending upwardly from the leg portions near their outer, free ends and a shield member extending upwardly from the inner edge of said intermediate portion and between the inner ends of the legs.

PHILIP J. DUGINSKI.
